COUNTER TOP COOKING UNIT

Lawrence Lerner, White Plains, N.Y., assignor to Michael Saphier Associates, Inc., New York, N.Y., a corporation

Filed May 17, 1961, Ser. No. 65,212

Term of patent 3½ years

(Cl. D81—25)

FIG. 2

FIG. 3

FIG. 4

FIG. 5

FIG. 1

FIG. 1 is a perspective view of a counter top cooking unit showing my new design;

FIG. 2 is a top plan view of the control portion of the cooking unit;

FIG. 3 is a side elevational view thereof;

FIG. 4 is a left edge elevational view thereof; and

FIG. 5 is a right edge elevational view thereof.

The dominant features of my design reside in the portions shown in full lines.

I claim:

The ornamental design for a counter top cooking unit, substantially as shown and described.
